his Attorney

UNITED STATES PATENT OFFICE.

JAMES H. REED, OF BURNS, OREGON.

PACKAGE-TIE.

1,353,611.

Specification of Letters Patent. Patented Sept. 21, 1920.

Application filed December 12, 1919. Serial No. 344,436.

To all whom it may concern:

Be it known that I, JAMES H. REED, citizen of the United States, residing at Burns, in the county of Harney and State of Oregon, have invented certain new and useful Improvements in Package-Ties, of which the following is a specification, reference being had therein to the accompanying drawing.

- 10 The primary object of the present invention has particular reference to a package tie embodying a flexible metallic plate with a button secured thereto and having a cord carried by said plate for wrapping about 15 a package or the like with the free end of the cord secured beneath the button and also includes the provision of a retaining device carried by the plate for the free end of the cord.
- 20 With the above and other objects in view, this invention consists in the novel form, combination and arrangement of parts herein fully described and shown in the accompanying drawing, wherein like reference 25 characters designate similar parts throughout the several views.

In the drawing,

Figure 1 is a top plan view of the present invention in operative position upon a package,

Fig. 2 is a side elevational view of the same with a portion of the package and cord broken away,

Fig. 3 is a developed top plan view of the tie fastener constructed in accordance with the present invention, and

Fig. 4 is an edge elevational view thereof.

Briefly described, the present invention includes a package tie embodying a plate 40 preferably formed of thin flexible metal, although heavy cardboard or the like could be employed and having a knotted end of a tying cord secured to one end thereof. A disk or button is carried by the opposite end 45 of the plate and is adapted to have the tying cord after winding around the package secured beneath the same, while a resilient tongue formed upon the edge of said plate and bent to overlie the same is adapted for 50 engagement with the free end of the cord for retaining the cord in position beneath the disk or button, and to prevent the cord from working loose upon the tie plate.

Referring more in detail to the accompanying drawing, there is provided a plate 55, preferably of the configuration illustrated

in Figs. 1 and 3, an enlargement 6 being formed integral therewith and having an opening 7 formed therein by which the tie plate may be suspended upon a file or other support when not in use. At the end of the plate 5 adjacent the opening 7, there is provided another opening 8 for the reception of the knotted end of the cord, presently to be described. The opposite end of the plate 65 5 upon the face thereof has riveted thereto, a disk or button 9 with the rivet 10 passing centrally therethrough and through the plate 5, while a cord receiving space 11 is provided between the disk 9 and plate 5 as 70 clearly illustrated in Fig. 4 for the reception of the tying cord.

A retaining spring finger 12 is formed integral with the edge of the plate 5 adjacent the cord receiving opening 8 and is bent 75 upon the line 13 to overlie the plate 5 as illustrated in Fig. 1 with the resilient projecting end 14 thereof adapted for the retention of the free end of the cord therebeneath.

In applying the tying device to the package A as illustrated in Figs. 1 and 2, the cord has the knotted end 15 thereof passed through the opening 8 and wrapped about the package in the direction as indicated at 85 16 over the sides and bottom, and upwardly over the opposite side of the top as at 17 for looping with the portion 16 and extending at right angles thereto as at 18 longitudinally of the package and returning as at 19 90 for passage beneath the button 9 as indicated at 20 in Fig. 1 for one complete wrapping beneath the disk 9 with the terminal end 21 of the tying cord received beneath the resilient connection 14 of the spring 95 finger 12. It will be seen from the above description of the device that a package may be securely tied with the present invention and the accidental displacement of the tying cord will be prevented in 100 view of the retention of the terminal end 21 thereof beneath the finger extension 14 while the cord will be previously retained beneath the button 9. When the device is out of use, the same may be easily suspended 105 upon a file or the like by hanging the same at the point 7 until it is again ready for use.

As illustrated in Fig. 1, the terminal end of the cord 21 extends in a line from the 110 button 9 to the finger extension 14 in a manner to retain the cord beneath the button.

While there is herein shown and described the preferred embodiment of the invention, it is nevertheless to be understood that minor changes may be made therein without departing from the spirit and scope of the invention as hereinafter claimed.

What is claimed as new is:—

1. A package tie comprising a flexible metallic plate provided at its edge with an outwardly projecting extension integral therewith, said extension having a tapered portion decreasing in width forwardly, said extension being bent upon its inner longitudinal edge to overhang the metallic plate with said portion bent upwardly at an angle with relation to the plate, a button secured to the top of the plate in alignment with the upwardly bent portion, and a cord secured to the plate near said extension and adapted to be passed about the package and about the

- 20

button with its free end inserted beneath the upwardly bent portion.

2. A package tie comprising a flexible metallic plate provided at its edge with an outwardly projecting extension integral therewith, said extension having a tapered portion and bent upon its edge to overhang the said plate, a button secured to the top of the plate, and a cord secured to the plate near said extension and adapted to be passed about the package and about the button with its free end inserted beneath the bent portion of said extension. 25

In testimony whereof I hereunto affix my signature in the presence of two witnesses. 30 35

JAMES H. REED. [L.S.]
